UNITED STATES PATENT OFFICE

BERTRAM B. GEYER, OF DAYTON, OHIO, ASSIGNOR TO FRIGIDAIRE CORPORATION, OF DAYTON, OHIO, A CORPORATION OF DELAWARE

REFRIGERATING APPARATUS

Application filed August 31, 1928. Serial No. 303,260.

This invention relates to refrigerating apparatus and more particularly to an ice cube forming attachment for the ordinary domestic mechanical refrigerating cabinet.

5 An object of this invention is to provide an ice cube freezing cabinet adapted to provide a relatively large number of ice cubes.

Another object of this invention is to provide a secondary ice cube freezing cabinet 10 adapted to be inserted in the unused machinery compartment of a domestic mechanical refrigerator cabinet when the refrigerating machinery for said refrigerator cabinet is installed outside of the cabinet.

15 Further objects and advantages of the present invention will be apparent from the following description, reference being had to the accompanying drawing, wherein a preferred form of the present invention is clearly shown.

In the drawings:

Fig. 1 is a front view of a refrigerator embodying features of my invention;

20 Fig. 2 is a side view partly in elevation and partly in section of the cabinet shown in Fig. 1;

Fig. 3 is a side elevation of the secondary ice cube freezing cabinet;

25 Fig. 4 is a horizontal cross sectional view of the lower portion of a domestic mechanical refrigerator embodying features of my invention;

Fig. 5 is a cross sectional view taken transversely to Fig. 4 on a slightly reduced scale;

30 Fig. 6 is a plan view of a device for attaching the metal ornamental front;

Fig. 7 is a cross sectional view of the device shown in Fig. 5 when used in the cabinet; and

35 Fig. 8 is a cross sectional view taken transversely to Fig. 6.

Some domestic mechanical refrigerators now on the market are provided with a food storage compartment in which an evaporator or cooling unit is generally placed. This 40 evaporator ordinarily is provided with a certain amount of ice cube forming capacity. This type of refrigerator ordinarily is also provided with a compartment in which the refrigerating machine is placed when the 45 cabinet is to be of the self-contained or port-

able variety. However, sometimes the refrigerating machinery is installed outside of the cabinet, for instance, in the basement of the residence in which the cabinet is to be installed, or in the basement of the apartment 55 house wherein the refrigerating machinery supplies liquid refrigerant to several cabinets. Also in restaurants, hotels, and ice cream parlors and the like the refrigerating machinery may be installed at a place remote 60 from the cabinet. It is contemplated, according to this invention, to provide a secondary ice freezing cabinet which, if desired, may be inserted in the unused machine compartment of the automatic domestic mechanical refrigerator cabinet, which secondary ice 65 cube freezing cabinet is adapted to provide an additional supply of ice cubes. This is particularly advantageous in hotels, restaurants and such other places where an unusually large demand for ice cubes may occur.

As an embodiment of this invention, there is illustrated in the drawings a cabinet generally designated as 20. This cabinet is termed herein a domestic mechanical refrigerator cabinet, although it is to be understood that this type of cabinet may be installed in 75 hotels, restaurants and such other places. The cabinet may be provided with a food storage compartment 21 and another compartment which is often used for refrigerating machinery and which is designated as 22. The food compartment 21 ordinarily is provided with insulation 23 and with a cooling unit 80 or evaporator 24. This cooling unit 22 may be supplied with refrigerant, either of the volatile or of the unvolatile type, from the refrigerating machinery which may be placed in the compartment 22 or which may be placed in some part of the building outside of the cabinet 20. The cooling unit 24 as herein shown may be used with volatile refrigerant, such as SO_2 , and may comprise a header 25 in which a float valve controls the entrance of the refrigerant through the fittings 26 and from which the evaporated refrigerant leaves through the pipe 27. This type of evaporator may be made in accordance with the disclosure in the patent to R. G. Osborne, 1,556,708 patented Oct. 13, 1925. 100

The evaporator may be provided, if desired, with ice cube forming means. This may comprise one or more sleeves adapted to receive ice cube forming trays 28 which ordinarily may be removed horizontally from the evaporator 24.

When a cabinet as heretofore disclosed is installed in a building with the refrigerating machinery outside of the cabinet, a secondary 10 ice cube freezing cabinet, contemplated in accordance with this invention, may be inserted in the unused machinery compartment 22, although under certain conditions the machinery may be placed in the compartment 22 15 and the secondary ice cube freezing cabinet may be placed outside of the cabinet 20. However, in the preferred form, the cabinet 20 may be connected with the refrigerating machinery installed outside of the cabinet 20 by means of the liquid refrigerant pipe 30 and the evaporated refrigerant pipe 27. The pipes 27 and 30 may be provided with T-fittings 31 and 32, respectively, directed toward the compartment 22. The secondary ice cube 25 freezing cabinet 35 may be inserted in the compartment 22 and the fittings 31 and 32 may be connected with the refrigerant pipes 33 and 34 respectively.

The secondary ice cube freezing cabinet, in 30 general, comprises an insulated evaporator provided with sleeves for the reception of ice cube trays. A specific embodiment may comprise a generally boxlike cabinet having a lining 36 to which an auxiliary evaporator 37 35 may be secured in any suitable manner such as by hangers 38. The lining 36 may be insulated by insulation 39 and an outer casing 40 may be placed around the insulation 39. At the front of the secondary cabinet 35 a 40 door jamb 41 may be provided. This door jamb may be of a size to fit snugly in the opening 42 of the compartment 22. The door jamb 41 may be a rectangular wooden frame to which the lining 36 may be secured. An insulated closure, or door, 43 may be mounted, 45 preferably by hinges, in the opening formed by the door jamb 41. The door jamb 41 may be provided with a metal front 44 of the same material as the outer casing of the main 50 refrigerator cabinet 20. The evaporator 37 may be, if desired, of the type disclosed in the application of Harold B. Wallis, Serial No. 164,712 filed January 31, 1927. In general it 55 may comprise a header 50 of the type disclosed in the patent to Osborne heretofore mentioned. The header may have depending refrigerant members or loops 51 surrounding ice cube tray sleeves 52 adapted to receive ice cube trays 53. The sleeves 52 60 may extend through a front metal piece 54 which may be secured to the sleeves 52. A metal front piece 55 provided with an opening for the insertion or the removing of the ice trays 53 may be mounted in front of the 65 evaporator 37.

Preferably the front 55 may be attached to the door jamb 41. A convenient method of attaching the front 55 may be by the fitting shown in Figs. 5, 6 and 7. These fittings may comprise a metal plate 60 provided with flanges 61 adjacent an opening 62 in the plate 60. A U-shaped metal piece 63 may be provided with ears 64 in the ends of its arms. A spring clip 65 may have the ends of a spiral spring inserted in holes 66 in the flange 61. A spiral spring 65^a may surround a metal bar 67 which is adapted to press against the flanges 64 of the U-shaped piece 63. When the metal front 55 is placed in the opening of the door jamb 41, the metal U-shaped piece 63 recedes into the cavity 68 and then snaps into openings 69 in the flanges of the front piece 55.

The pipes 33 and 34 may lead through a wall of the cabinet 35 to fittings in front of the header 50. These fittings are mounted on a removable plate carrying a float controlled valve and an evaporated refrigerant outlet fitting, for instance of the type shown in the hereinbefore mentioned patent to Osborne.

The food compartment 21 may be provided with a drain 70 which is adapted to receive the water dripping from the cooling unit 24 when the unit is being defrosted. The drain 70 may be coupled to the drain 71 of the cabinet 35 and the two may be connected to the main drain 72 connected to the plumbing of the building in any convenient manner.

It is thus seen that there is provided, according to this invention, an insulated cooling unit or evaporator provided with an opening for the reception of ice cube trays and with an insulated closure for said openings. Within the insulation of the evaporator substantially all of the specific and latent "cold" is removed from the refrigerant to form ice cubes. The refrigerant entering and leaving through pipes 34 and 33 is substantially at atmospheric temperature. Thus the forming of ice cubes is the entire task of the refrigerant. Preferably the insulated evaporator is adapted to fit in the usual machinery compartment of the main cabinet, although under certain conditions, it may be used independently of the cabinet. When inserted into the main cabinet 20, the secondary cabinet may be provided with a base 75 to which the outer casing 40 may be attached, and the base 75 may rest on the lower framework 76 of the main cabinet 20. The cabinet 35 may then be secured in place by any suitable means such as wooden screws 77. The door 43 preferably is hinged to the cabinet 35, although, under certain conditions, the door may be hinged to the main cabinet.

While the form of embodiment of the invention as herein disclosed, constitutes a preferred form, it is to be understood that other

forms might be adopted, all coming within the scope of the claims which follow.

What is claimed is as follows:

1. A refrigerating apparatus comprising a mechanical refrigerator cabinet having an insulated food compartment provided with an iceless cooling unit and another compartment provided with an opening, and a secondary cabinet inserted in said last named compartment and closing said opening, said secondary cabinet being provided with an insulated ice cube freezing unit having removable ice cube trays, and an opening with an insulated door for the removal of said trays.

2. A secondary ice cube freezing cabinet to be inserted in the unused machinery compartment of a domestic mechanical refrigerator cabinet, the refrigerating machinery of which has been installed outside of said refrigerator cabinet, which secondary cabinet comprises an evaporator having ice cube tray sleeves, insulation closely related to said evaporator, the front of said secondary cabinet fitting in the usual opening of said machinery compartment, said front being provided with an opening for the removal and insertion of ice cube trays from and in said ice cube tray sleeves, and an insulated door for closing said last named opening.

3. A secondary ice cube freezing cabinet to be inserted in the unused machinery compartment of a domestic mechanical refrigerator cabinet, the refrigerating machinery of which has been installed outside of said refrigerator cabinet, which secondary cabinet comprises an evaporator having ice cube tray sleeves, insulation closely related to said evaporator, the front of said secondary cabinet fitting in the usual opening of said machinery compartment, said front being provided with an opening for the removal and insertion of ice cube trays from and in said ice cube tray sleeves, and an insulated door for closing said last named opening, said door being carried by said secondary cabinet.

4. A secondary cube freezing cabinet adapted to be inserted in the unused machinery compartment of a domestic mechanical refrigerator cabinet, the refrigerating machinery of which has been installed outside of said cabinet, which secondary cabinet comprises an evaporator having ice cube tray sleeves, insulation closely related to said evaporator, the front of said secondary cabinet being adapted to fit in the usual opening of said machinery compartment, said front being provided with an opening for the removal and insertion of ice cube trays from and in said ice cube tray sleeves, an insulated door for closing said last named opening, and a metal front for said evaporator having openings for said sleeves, said metal front having quick attaching means for attachment of said front to said secondary cabinet.

5. A refrigerating apparatus comprising a

mechanical refrigerator cabinet having an insulated food compartment provided with an iceless cooling unit and another compartment provided with a secondary cabinet inserted in said last named compartment, said secondary cabinet being provided with an insulated ice cube freezing unit having removable ice cube trays, an opening with an insulated door for the removal of said trays, said cooling unit and said ice cube freezing unit being connected to the same refrigerant liquefying unit.

6. A refrigerating apparatus comprising a mechanical refrigerator cabinet having an insulated food compartment provided with an iceless cooling unit and another compartment provided with a secondary cabinet inserted in said last named compartment, said secondary cabinet being provided with an insulated ice cube freezing unit having removable ice cube trays, an opening with an insulated door for the removal of said trays, said cooling unit and said ice cube freezing unit being connected to the same refrigerant liquefying unit, said refrigerant liquefying unit being installed outside of said refrigerator cabinet.

7. A refrigerating apparatus comprising a mechanical refrigerator cabinet having an insulated food compartment provided with an iceless cooling unit and another compartment having an opening, a secondary cabinet inserted in said last mentioned compartment, an insulated ice cube freezing unit in said secondary cabinet, the front of said secondary cabinet fitting snugly in the opening of said last mentioned compartment.

In testimony whereof I hereto affix my signature.
